ROTARY KILN

Ray C. Newhouse, Wauwatosa, Wis., assignor to
 Allis-Chalmers Manufacturing Company, Milwaukee, Wis., a corporation of Delaware

Application August 20, 1934, Serial No. 740,663

20 Claims. (Cl. 263—33)

This invention relates in general to apparatus for drying and heat treating materials, and in particular to rotary kilns of the type utilizing chains or similar flexible elements for transferring heat to material being treated.

In apparatus of this type as constructed heretofore, the chains have been suspended in such manner that they seriously interfere with the flow of material through the kiln and do not sufficiently intercept the flow of hot gases through the kiln. In some kilns as heretofore constructed the chains are drawn taut across the kiln interior with the result that they either do not dip into the material at the bottom of the kiln when it is rotated, or if they are so positioned as to dip into the material when at the bottom of the kiln, they do not hang down into the stream of hot gases when at the top of the kiln but leave a large opening free for the flow of gases through the kiln without coming in contact with the chains. In either event they seriously obstruct the movement of material through the kiln.

In an attempt to correct this difficulty, chains have been suspended in kilns with slack with the undesired result that the chains when positioned at the bottom of the kiln fold upon themselves and form a large tumbling mass which obstructs the normal flow of material through the kiln and results in excessive wear of the chains and of the kiln lining. Further, the slack chains when in suspended position in the kiln tend to so hang as to form a dense network near the bottom of the kiln, leaving the top of the kiln open and permitting the hot gases to pass along the top of the kiln without contacting with the main portion of the chain system. Because of the fact that the slack chains do not efficiently engage the hot gases and the fact that a large amount of slack chain is at all times submerged in the material being treated, it has been necessary in kilns of this type as previously constructed to install an excessive amount of chains to effect the required transfer of heat to the material being treated.

It is the general object of this invention to overcome the difficulties previously met with in chain kilns by providing an arrangement of chains for a rotary kiln which functions efficiently in transferring heat from the hot kiln gases to the material being treated.

A more specific object of the invention to this end is to provide an arrangement of chains in a rotary kiln whereby the greatest concentration of suspended chains occurs at the top of the kiln in the normal path of the hottest kiln gases.

Another object of the invention is to provide a chain system for a rotary kiln in which the density of the suspended chain curtain decreases from the top toward the bottom of the kiln.

Another object of the invention is to provide a chain system for a rotary kiln in which the chains are so suspended as to provide a free space just above the bottom of the kiln to induce the hot kiln gases to flow directly over the material in the bottom of the kiln.

Another object of the invention is to provide a chain system for a rotary kiln in which the chains are so suspended that when they are at the bottom of the kiln, they conform to the interior surface thereof to permit the material being treated to advance over them through the kiln.

Another object of the invention is to so suspend the chains in a rotary kiln as to prevent tumbling thereof on the bottom of the kiln to thereby avoid excessive wearing of the chains and of the kiln liner.

Another object of the invention is to provide a chain system for a rotary kiln including the combination of a plurality of long relatively heavy chains so suspended as to hang into the lower portion of the kiln, and a plurality of short relatively light chains so suspended as to form a dense chain curtain near the top of the kiln.

A further object of the invention is to provide a chain curtain for a rotary kiln formed of units, each unit comprising sequentially arranged chains in a transverse plane of the kiln and successive units being displaced angularly to form a composite interlacing curtain.

A further object of the invention is to provide a novel chain attachment block for a chain kiln.

In practicing the improvements of the present invention, the chains in a kiln are arranged in a series of chain units disposed in spaced transverse planes of the kiln. Each unit is formed by a plurality of relatively heavy chains of different lengths, each chain being attached at its ends to the interior of the kiln at points spaced circumferentially and each chain being of length equal to the circumferential distance between the points of attachment of its ends. The chain units are each formed with chains arranged sequentially around the kiln and successive units are displaced angularly in such manner that the chains form a continuous interlaced network or curtain, the length of the chains being so chosen that the chain curtain formed by them is of progressively less density toward the bottom of the kiln. At the cooler end of the kiln additional relatively short light-weight chains are provided to

form a chain curtain of great density near the top of the kiln.

The stated, as well as other objects of the invention will be more fully apparent from the following description of a particular embodiment of the invention that is shown by way of illustration in the accompanying drawing, the several views of which are as follows:

Figure 1 is a view in side elevation of a rotary kiln illustrating diagrammatically the disposition therein of a chain system embodying the present invention;

Figure 2 is a development showing the interior of the upper or inlet end portion of a rotary kiln and illustrating diagrammatically the position at which the ends of the chains are attached to the kiln interior in accordance with the present invention;

Figure 3 is a view in cross section of a kiln taken on the plane represented by the line III—III in the development of Figure 2 and showing the single chain unit in that plane;

Figure 4 is a view in cross section taken on the plane represented by the line IV—IV in the development of Figure 2 and showing only the single chain unit disposed in that plane;

Figure 5 is a view in cross section taken on the plane represented by the line V—V in the development of Figure 2 looking in the direction of the arrows and showing all of the chains of the first chain set;

Figure 6 is a view in cross section taken on the units in the plane represented by the line VI—VI in the development of Figure 2 looking in the direction of the arrows and showing all of the chains of the first chain group;

Figure 7 is an enlarged detailed view in cross section of an attaching block for securing the chain ends to the kiln interior, taken on the plane represented by the line VII—VII in Figure 8;

Figure 8 is a fragmentary view of the attaching block partly in side elevation and partly in longitudinal section taken on the plane represented by the line VIII—VIII of Figure 7;

Figure 9 is a view similar to Figure 7 of an attaching block for use in the hotter portion of the kiln and taken on the plane represented by the line IX—IX of Figure 10; and

Figure 10 is a view similar to Figure 8 showing the attaching block illustrated in Figure 9 partly in side elevation and partly in longitudinal section taken on the plane represented by the line X—X of Figure 9.

Referring more particularly to the drawing, the rotary kiln 1 illustrated in Figure 1 by way of example as a practical structure embodying the present invention, is of the well known type used in the manufacture of Portland cement or the like. A kiln of this type is usually divided generally into a burning zone at the lower end thereof and a drying zone at the upper end. The present invention is particularly concerned with the drying zone of the typical kiln illustrated, although it is to be understood that the invention may be applied to rotary kilns of other types or to rotary drying drums used separately for drying material.

As shown in Figure 1, the typical rotary kiln 1 comprises essentially a rotatably mounted cylindrical drum or shell 2 disposed in inclined position in the usual manner and arranged to receive wet material to be treated from a spout 3 which enters the inlet end 4 of the kiln. For providing hot gases to dry and burn the material within the kiln, a removable firing hood 6 provided with a burner 7 is applied to the discharge end 8 of

the kiln. The firing hood 6 is arranged in well known manner to cause a flow of hot gases longitudinally through the kiln shell 2 from the discharge end 8 thereof to the inlet end 4, where the spent gases are collected in a housing 5 from which they may be conveyed away to be discharged by a chimney or the like in the usual manner.

The wet material, for example, wet cement slurry, which enters the inlet end 4 of the kiln 10 through the spout 3, is caused to advance through the kiln in the usual manner by slowly rotating the kiln shell by means of a ring gear 9 that encircles and is attached to the shell and which is driven by a meshing pinion 10 rotatably mounted 15 in a supporting bearing 11.

In progressing through the kiln shell 2, the wet material engages in the upper or drying end of the shell with the chains of a chain system embodying the present invention and is elevated 20 thereby into contact with the hot kiln gases. The extent of the entire chain system in the kiln shell 2 is indicated in Fig. 1 by the bracket 12. The material to be treated enters the kiln in wet and cool condition and is first acted upon by the 25 chains in the zone of the chain system that is indicated by the bracket 13 in Fig. 1. This zone of the system includes a large number of relatively light short chains in addition to sets of longer relatively heavy chains arranged around the inner 30 circumference of the shell 2. In passing through the zone 13 of light and heavy chains, the material being treated is dried and heated to such an extent that its cooling action upon the chains is no longer sufficient to prevent light chains 35 in the chain system from being quickly destroyed by the hot kiln gases. Consequently, in the remaining zone of the chain system, indicated by the bracket 14, only the heavier chains are utilized.

After the material being treated has passed 40 through both of the chain zones 13 and 14 of the chain system 12, it is first calcinated and then clinkered in the burning zone of the kiln and subsequently discharged from the discharge end 8 of the shell 2 through the firing hood 6 in the usual 45 manner.

In the process of treating the wet material in the drying zone of the kiln containing the chain system 12, it is desirable that as much as possible of the material be elevated by the chains to the 50 top part of the kiln in order to bring it into contact with the hottest kiln gases which normally pass along the kiln just beneath the top of the shell. Further, it is desirable that as much as possible of the chains be exposed to the hot gases 55 in the top portion of the kiln in order that the chains may be heated for subsequently conveying the heat thus absorbed to the material at the bottom of the kiln when they are rotated into contact with it. It is also desirable that the flow of 60 the hot gases along the top portion of the kiln 2 be intercepted and retarded in such manner as to tend to force the hot gases downward into contact with the material at the bottom of the kiln.

To accomplish these results the chains of the 65 chain system are arranged, in accordance with the present invention as shown in the cross sectional view in Figure 6, in such manner that the suspended chains form a curtain of relatively dense texture at the top of the kiln and of diminishing density downward toward the bottom 70 of the kiln, leaving an open space just above the kiln bottom for the free flow of hot gases directly over the material at the bottom of the kiln. Further, as shown in Figure 6, the chains in the 75

kiln are so arranged that they conform to the interior surface of the kiln when they are resting on the bottom thereof in such manner as to permit the material being treated to advance over them 5 through the kiln without being unduly obstructed.

In suspending the chains in this manner in accordance with the present invention, the chains are arranged, as illustrated in Fig. 2, in a plurality of circular chain units each disposed in a 10 transverse plane of the kiln. Each chain unit includes a plurality of chains of different lengths suspended from the interior surface of the kiln shell 2 in such manner that when adjacent units are suitably displaced angularly relative to each 15 other, the desired arrangement of chains shown in Figure 6 is obtained.

Referring particularly to Figures 3 and 4 which show similar individual chain units 51 and 55 displaced 180° relative to each other, the particular 20 arrangement of chains shown for practicing the invention includes in each chain unit two long heavy chains 15 of equal length connected at their ends to attachment points spaced at 135° and one shorter heavy chain 16 attached at its ends to 25 attachment points spaced at 90°. As the total of the attachment point spacing angles constitutes 360°, the ends of the three chains are connected to three common suitably spaced attachment points in such manner that the chains of the unit 30 are arranged in sequence forming a continuous chain circle around the kiln interior. In order that the chains may conform to the inner surface of the kiln when resting on the bottom thereof, each of the chains 15 and 16 is formed of length 35 approximately equal to the circumferential distance between the attachment points for its ends.

For convenience in laying out the positions for the chain attachment points in the kiln and in providing suitable securing means for the chain 40 ends, the chain units of the chain system are arranged in sets, each set being indicated by the numeral 21 in Figure 2. The successive chain units of each set 21 are progressively displaced angularly by an angle that is a common divisor 45 of the angular spacing of the chain end attachment points of each unit. In the particular arrangement shown in the drawing, the successive chain units of each chain set 21 are displaced progressively through an angle of 45°, whereby 50 all of the end supporting points of both the 135° and the 90° chains occur in a series of longitudinal lines spaced at 45° upon the interior of the shell 2. With the adjacent chain units displaced through 45°, a complete cycle of angular displacement is effected in eight successive displacements, consequently eight successively displaced chain 55 units 51 to 58 are grouped together in forming one complete chain set 21. The composite chain curtain formed by the first chain set 21 of eight 60 chain units is shown in Figure 5.

As the attachment points for the ends of the chains in the units 51 to 58 of each set 21 are arranged in alignment on longitudinal lines spaced at 45° intervals, it is convenient to provide 65 a series of longitudinally disposed attachment blocks 19 arranged circumferentially of the kiln and spaced at 45° intervals for receiving the ends of the chains of each chain set 21, as indicated diagrammatically in Figure 2 of the drawing. In the zone 13 at the upper end of the kiln containing both light and heavy chains, the attachment blocks 19 also serve to secure the ends of short light chains 17 extending between adjacent blocks.

75 The points of attachment of the ends of the

heavy chains 15 and 16 to the blocks 19 are indicated in Figure 2 by the centrally disposed small circles 40. For instance, in the first chain set 21 the attachment point at position 74 for the chains 15 of the first chain unit 51, shown at the 5 top of the kiln shell in Figure 3 is represented in Figure 2 by the circle 40 in the plane indicated by the line III—III at the intersection thereof with the line 60—60, which is designated attachment position 74 in this figure also. The points 10 40 above and below position 74 on the line 60—60, at attachment positions 71 and 77 respectively in the plane III—III of Figure 2, are each spaced therefrom through an angular distance of 135° and these points at positions 71 and 77 are spaced 15 from each other through an angle of 90°, completing the circle of the first chain unit 51.

As shown in Figure 3, the two long heavy chains 15 of the first chain unit 51 are both attached at one end to the attachment block at 20 position 74 and are attached at their other ends respectively to the attachment blocks at positions 71 and 77, the short heavy chain 16 being connected between these latter two blocks. In Figure 4, the short heavy chain 16 of chain unit 25 55 is shown suspended at its ends from attachment blocks at positions 73 and 75 and the two long heavy chains 15 are respectively suspended at one end from the attachment blocks at positions 73 and 75 and are attached at their other 30 ends to a common attachment block at position 78.

Starting with the attachment point 40 at position 71 at the top of Figure 2 in the plane III—III containing chain unit 51, it may be seen 35 that corresponding attachment points in the successive chain units 52 to 58 are displaced progressively through angles of 45° to the successive positions 72 to 78 respectively, as indicated by the diagonal broken line 41. The attachment point 40 to which the ends of the 135° chains 15 of the chain unit 55 in the plane IV—IV are connected and which corresponds to the attachment point of the chains 15 of chain unit 51 at position 74 at the top of the kiln shell 45 in Figure 3, is displaced therefrom through four increments of 45° or a total of 180°, bringing it to position 78 at the bottom of the kiln, as shown in Figure 4. In the composite set 21 of the eight chain units 51 to 58 shown in Figure 5, it may be 50 seen that the longer chains 15 form the portion of the network near the bottom of the kiln and that the shorter chains 16 cooperate with the long chains 15 and with the light chains 17 to form the denser network near the top of the 55 kiln.

To effect angular offsetting of the chains of adjacent chain sets 21, the chain sets are arranged in groups 22 of three sets each, each set 21 of chain units in a group 22 being displaced 60 15° relative to the adjacent chain set 21, whereby the three sets 21 form a complete cycle for the group. The composite curtain of chains formed by one group 22 of three sets 21 is shown in Figure 6.

In order that the chains of adjacent chain groups 22 may be angularly offset, each chain group 22 is displaced angularly through an angle of 3° relative to the adjacent chain group. This is accomplished by positioning the attachment 70 blocks 19 of the first chain set 21 in one group at an angle of 18° instead of 15° relative to the blocks 19 of the last chain set 21 in the previous group 22 as may be seen by referring to Figure 2. To constitute a complete kiln cycle 23, a total of 75

five groups 22, each displaced 3° relative to the adjacent group, is required.

In the portion of the chain system 12 indicated by the bracket 13 in Figure 1 the heavy chains

- 5 15 and 16 are supplemented by a plurality of light chains 17 which are connected at their ends to adjacent attachment blocks 19 spaced at 45° and are of length equal to the circumferential distance between these blocks. These chains 10 are connected to the blocks 19 at attachment points which are indicated in Figure 2 by the small circles 42 along the edges of each block. In practicing the invention, the light chains 17 are ordinarily positioned closer together than is 15 indicated by the attachment points 42 shown in Figure 2, usually being placed in such manner that they cover substantially the entire inner surface of the kiln when they are resting on the bottom thereof.

- 20 The position taken by the light chains 17 is illustrated in Figures 3, 4, 5 and 6 of the drawing. Figure 6 shows clearly the manner in which the light chains 17 cooperate with the heavy chains 15 and 16 to form a composite chain net-work of great density at the top portion of the kiln and of diminishing density toward the bottom of the kiln. This dense network of chains lifts a large amount of the material being treated into contact with the hot kiln gases at the top 30 of the kiln as the kiln is rotated and constitutes a barrier tending to force the kiln gases downward into the free space just above the material at the bottom of the kiln. By this arrangement of chains, more effective drying action is obtained than by the previously used chain systems, and the material of the chains is operated at much greater drying efficiency than that of chains as heretofore utilized.

- 35 The attachment blocks 19, which are shown in detail in Figures 7 and 8, each comprises a cast or forged metal block provided with end flanges 24 for receiving attaching bolts 25 by means of which the block may be rigidly secured to the inner surface of the kiln shell 2. The blocks 19 are of such height that they extend inwardly from the shell 2 a sufficient distance to provide space for a lining 18 of firebrick or other suitable material within the kiln shell 2. Each block is formed hollow with a longitudinally extending recess or cavity 26 in its lower portion adjacent to the shell 2. The inwardly extending portion of each block 19 is provided with a longitudinal slot 30 for receiving bolts 29 that serve to secure the ends of the heavy chains to the block. Transverse webs 61 are provided in the cavity 26 of each block to strengthen it and openings 27 are formed through the transverse webs to permit movement therethrough of the heads of the bolts 29. Beneath the openings 27 a central longitudinal web 28 is disposed in the cavity 26 to act as a stop for the heads of the bolts 29 to prevent them dropping into the cavity 26. Rectangular notches or depressions 38 are formed at spaced positions in the body of the block above the web 28 for receiving the square heads of the bolts 29 in order to position them in the transverse planes of the chain units. Each bolt 29 is provided at its outer end with a clamp member 31 having opposed hook portions 32 disposed to pass over the end links of the heavy chains 15 or 16 and to engage in seats 39 in the outer surface of the block 19 to securely retain the chain ends when the nuts on the ends of the bolts 29 are tightened.

- 75 For receiving the light chains 17 the sides of

each block 19 are provided with spaced recesses 33 each adapted to receive the end link of a chain. The chain end links are secured in the recesses 33 by means of longitudinally extending rods or bolts 35 passing through longitudinal openings 34 in the block 19 and through the end links within the recesses. As shown in Figure 8, the recesses 33 for receiving the end links of the chains 17 are closely positioned in such manner as to receive a sufficient number of the light 10 chains 17 to substantially cover the entire inner surface of the kiln. Although the attaching points for the light chains 17 are indicated diagrammatically in Figure 2 by the small circles 42 as being in the planes of the attachment points 15 40 of the large chains for the sake of simplicity in illustration, the link receiving recesses 33 are not necessarily positioned in definite relation to the clamp members 31 but may be arranged entirely independent thereof as shown in Figure 8. 20

In the portion of the chain system 12 indicated by the bracket 14 in Figure 1 in which no light chains 17 are used, the attachment blocks 20 shown in Figures 9 and 10 having means for attaching heavy chains only are utilized. As 25 shown in Figures 9 and 10, each block 20 is similar in general to the blocks 19 shown in Figures 7 and 8 but is not formed as high as the block 19 as it is not necessary to provide space for the attachment of chains to its sides, and consequently the longitudinal interior recess 36 thereof is not as large as the recess 26 in the block 19. As in the case of the blocks 19, each block 20 is provided with end flanges 24 and securing bolts 25 and with a longitudinal slot 30 communicating 35 with the recess 36 for receiving the bolts 29 which secured the clamp members 31 for receiving the end links of the heavy chains 15 and 16. Beneath the slot 30 a longitudinally disposed web 37 is provided for engaging the heads of the bolts 40 29 to retain them within the block.

Although the chain system disclosed herein has been shown applied only in one specific way to one type of kiln, it is to be understood that chain systems embodying the invention defined in the 45 subjoined claims may be applied by those skilled in the art to other types of kilns or similar apparatus without departing from the spirit of the invention.

It is claimed and desired to secure by Letters 50 Patent:

1. A chain system for a rotary kiln, comprising a plurality of relatively light chains suspended within the shell of the kiln to hang in a dense mass near the top thereof to intercept the 55 hot kiln gases in the upper portion of the kiln, and a plurality of relatively heavy chains suspended to cooperate with said light chains to form a composite chain curtain of progressively decreasing density from the top to the bottom of 60 the kiln.

2. A chain kiln, comprising a rotatably mounted drum, a plurality of chains suspended within said drum, said chains being arranged to form a curtain therein of great density at its upper 65 portion and of decreasing density downwardly therefrom terminating at an open lower portion just above the material being dried in the bottom of the drum, whereby hot gases passing through said drum engage said chains at the upper part thereof and are urged downwardly thereby into contact with the material in the bottom of the drum.

3. A rotary kiln for heat treating material, comprising a rotatably mounted drum, means for 75

feeding material to be treated into one end of said drum for advancement therethrough, means for passing heated gases through said drum, and a plurality of chains attached to the interior of said drum for elevating said material into contact with said heated gases, each chain being attached at its ends at points spaced circumferentially a distance substantially equal to the length of said chain, said chains forming a chain curtain of dense texture at the top of the drum for engaging the hot gases and of diminishing density towards the bottom of the drum for urging the hot gases downward and providing an aperture at the bottom of the drum, permitting free passage of the hot gases over the material being treated at the bottom of the drum, said chains at the bottom of the drum substantially conforming to the inner surface thereof to permit free progression of the material thereover through the kiln.

4. A chain kiln, comprising a rotatably mounted drum, and a chain unit disposed in a transverse plane of said drum, said chain unit including one chain attached at its ends to the interior surface of said drum points spaced at 90° thereon and two chains each attached at one end to the respective end attachment points of said 90° chain and attached at their other ends to a common attachment point midway between and diametrically disposed with respect to said end attachment points of said 90° chain.

5. A chain kiln, comprising a rotatably mounted drum, and a circular chain unit disposed in a transverse plane of said drum, said chain unit including one chain attached at its ends to the interior surface of said drum at attachment points spaced at 90°, said chain being of length equal to the circumferential distance between said attachment points, and two chains each attached at one end to the respective end attachment points of said 90° chain and at their other ends to a common attachment point disposed 135° from said 90° attachment points, said 135° chains each being of length equal to the circumferential distance between the attachment points of its ends.

6. A rotary kiln comprising a rotatably mounted tube that constitutes a burning zone and a drying zone, a plurality of chains suspended within said drying zone, said chains being attached at their ends to the inner surface of said tube and disposed in circular units in spaced transverse planes, each transverse plane chain unit comprising one chain attached at its ends at points spaced at 90° and of length equal to the circumferential distance between said points of attachment and two chains each attached at one end to an end attachment point of said first chain and at the other end to a mutual attachment point midway between said first attachment points and each of length equal to the circumferential distance between said attachment points, the chain units in adjacent planes being displaced angularly relative to one another, whereby a composite chain curtain is formed in said drying zone of relatively dense structure at the upper portion of said drum and of relatively open structure at the lower portion thereof.

7. A rotary drier, comprising a rotatably mounted tube, a plurality of chains suspended within said tube said chains being arranged in circular units disposed in spaced transverse planes, the chains of each unit including one chain supported at its ends at points spaced 90° upon the interior of the tube and two chains supported at their ends at points spaced 135°

forming a continuous chain unit around the tube, the said chains being of lengths equal to the circumferential distances between the supporting points of their ends, said circular chain units being arranged in sets with the chains of adjacent units displaced angularly but with their points of support in longitudinal alinement to facilitate attachment thereof to the tube, said sets of chain units being displaced angularly to misalign them and arranged in groups, the sets of each group being displaced successively an equal amount and said groups being displaced angularly to dispose the sets of adjacent groups in alternate relationship.

8. A rotary kiln for heat treating material, comprising a rotatably mounted drum, a plurality of equally spaced attachment members secured upon the interior of said drum, and a plurality of heat transferring members arranged in circular units, each unit comprising a plurality of chains each attached at each end to noncontiguous attachment members forming a sequential arrangement, said units being displaced angularly relative to each other to form a composite chain set.

9. In a chain kiln, the combination with a rotatably mounted drum, of a plurality of attachment blocks for chain ends mounted in spaced relation upon the interior surface of said drum; each of said attachment blocks comprising a body portion having a longitudinally extending bolt receiving slot, bolt head receiving sockets in spaced positions along the inner edge of said slot, chain end link receiving sockets arranged along the sides of said body, and longitudinal passages intersecting said link receiving sockets; a plurality of bolts disposed in said longitudinal slot with their heads engaging predetermined ones of said bolt head receiving sockets, chain end clamping members carried by said bolts in position to extend through chain end links and clamp against said body portion to retain said links, and rods extending through said longitudinal passages and said link receiving sockets in position to pass through chain end links therein to retain them in said sockets.

10. In a rotary kiln, the combination with a rotatably mounted kiln shell, of a chain system mounted therein, comprising eight chain attachment blocks secured to the inner surface of the kiln shell and arranged circumferentially thereof at 45° intervals, and eight chain units arranged in parallel planes and carried by said attachment blocks each chain unit including a chain of length equal to the circumferential distance between blocks spaced at 90° said chain being attached at its ends to blocks so spaced, and two chains of length equal to the circumferential distance between blocks spaced at 135° each attached at one end to one of the blocks supporting the said 90° chain and each attached at the other end to a common block positioned at 135° from said 90° spaced blocks, said chains of each unit lying in a transverse plane of said kiln shell and the chains of adjacent units being displaced angularly successively to constitute a composite chain system.

11. A rotary kiln chain system, comprising a plurality of chain attachment blocks disposed in equally spaced relation on the inner surface of a rotary kiln shell defining a series of kiln segments therebetween, a plurality of light weight chains of length equal to one of said segments each disposed to subtend one of said segments with its ends attached to the attachment blocks delimit-

- ing said segment, a plurality of heavy weight chains of length equal to two of said kiln segments each disposed to subtend two segments with its ends attached to the attachment blocks delimiting said two segments, and a plurality of heavy weight chains of length equal to three of said kiln segments each disposed to subtend three segments with its ends attached to the attachment blocks delimiting said three segments.
10. 12. In a rotary kiln chain system, the combination with a rotatable kiln shell, of a plurality of chain attachment blocks disposed on the inner surface of said rotatable kiln shell at positions spaced 45° circumferentially and defining 45° kiln segments therebetween, a plurality of chains of length equal to the circumferential length of one 45° kiln segment each attached at its ends to adjacent attachment blocks delimiting one kiln segment in manner to hang in generally horizontal position when in the top portion of the kiln to form a dense chain curtain near the top of the kiln, a plurality of chains of length equal to the circumferential length of two kiln segments each attached at its ends to attachment blocks spaced at 90° in manner to hang in generally horizontal position across the upper portion of the kiln to form a dense chain curtain therein, and a plurality of chains of length equal to the circumferential length of three kiln segments each attached at its ends to attachment blocks spaced at 135° in manner to hang in generally vertical position to the bottom of the kiln at the sides of the center thereof and in generally horizontal position across the kiln below its center to form a chain curtain in the lower position of the kiln defining a relatively narrow unobstructed passageway along the bottom of the kiln.
13. In a rotary kiln chain system, a rotary kiln shell, a plurality of chain attachment blocks disposed on the inner surface of the rotary kiln shell at positions spaced 45° circumferentially and defining included kiln segments therebetween, a plurality of chains of length equal to the circumferential length of two of said included kiln segments each attached at its ends to attachment blocks spaced at 90° to hang in generally horizontal position across the upper portion of the kiln, individual chains being disposed in different planes and at different angular positions to form a dense chain curtain in the upper portion of the kiln, and a plurality of chains of length equal to the circumferential length of three of said included kiln segments each attached at its ends to attachment blocks spaced at 135° to hang in generally horizontal position across the kiln below its center or in generally vertical positions at the sides of the kiln center from the top to the bottom thereof, individual chains being disposed in different planes and at different angular positions to form an arched chain curtain in the lower portion of the kiln defining a relatively narrow unobstructed passageway along the bottom of the kiln shell.
14. In a rotary kiln having a rotatable kiln shell, a chain system comprising a plurality of chain attachment blocks arranged on the inner surface of the rotatable kiln shell in circumferentially spaced relation and defining therebetween equal included kiln segments defining an acute angle, a plurality of chains equal in length to the circumferential length of two of said segments said chains each being suspended at its ends from attachment blocks delimiting two contiguous segments and individual chains being disposed in different transverse planes and at different angular positions to form a dense chain curtain in the upper portion of the kiln, and a plurality of chains equal in length to the circumferential length of three of said segments said chains each being suspended at its ends from attachment blocks delimiting three contiguous segments and individual chains being disposed in different transverse planes and at different angular positions to form a chain curtain extending to the bottom of the kiln at the sides of its center and defining a relatively narrow unobstructed passageway along the bottom of the kiln shell.
15. A rotary kiln chain system, comprising a rotatable kiln shell, a plurality of chain attachment blocks disposed in spaced relation on the inner surface of said rotatable kiln shell, a plurality of light weight chains of length substantially equal to the circumferential distance between adjacent attachment blocks each attached at its ends to adjacent attachment blocks in such manner as to hang when in the upper part of the kiln in generally horizontal position near the top of the kiln, a plurality of heavy weight chains of length substantially equal to the circumferential distance between alternate attachment blocks each attached at its ends to alternate attachment blocks in such manner as to hang when in generally horizontal position across the upper portion of the kiln, and a plurality of heavy weight chains of length substantially equal to the circumferential distance between each third attachment block each attached at its ends to two attachment blocks spaced by three included blocks in such manner as to hang when in generally horizontal position across the kiln below its center and to hang when in generally vertical position into the lower portion of the kiln at one side of the center to define a narrow unobstructed passageway for hot gases along the bottom of the kiln shell.
16. In a rotary kiln of the type having chains suspended therein, a chain supporting block attached to the inner surface of said kiln, said block having openings along its sides for receiving the end links of chains, and a rod disposed longitudinally of said block and adjacent said openings in position to pass through chain end links to retain them within said openings.
17. A rotary kiln comprising a rotatably mounted kiln shell, a plurality of chain attachment blocks disposed longitudinally of said kiln in circumferentially spaced relation on the inner surface of said kiln shell, said blocks having openings for receiving the end links of chains, a plurality of chains disposed with their end links extending into said openings in said blocks, and rods passing through said chain end links within said openings to secure said chains to said blocks.
18. In a chain kiln, means for attaching the ends of chains to the inner surface of the kiln, comprising attachment blocks arranged in spaced relation upon the inner surface of the kiln, each of said blocks having means arranged centrally along the face of its inwardly extending portion for securing the ends of long chains and having openings along the sides of its inwardly extending portion for receiving the end links of short chains, and means for retaining chain end links within said side openings.
19. In a chain kiln, means for attaching the ends of chains to the inner surface of the kiln, comprising a plurality of attachment blocks arranged in spaced relation upon the inner surface of the kiln, each of said blocks having openings

along its sides for receiving the end links of chains, and means within said blocks for retaining chain end links within said openings.

20. In a chain kiln, the combination with a rotatably mounted shell, of a plurality of attachment blocks each adapted to engage the ends of a plurality of chains, said attachment blocks being arranged upon the inner surface of said

shell in circumferentially alined rows, the blocks of each row being equally spaced angularly and said rows of blocks being disposed in groups with the rows of each group displaced angularly relative to each other and with the groups displaced angularly relative to one another. 5
